ATTORNEYS

UNITED STATES PATENT OFFICE.

DWIGHT W. WADSWORTH, OF FENNVILLE, MICHIGAN.

SORTING MACHINE.

Application filed March 12, 1924. Serial No. 698,809.

To all whom it may concern:

Be it known that I, DWIGHT W. WADSWORTH, a citizen of the United States, residing at Fennville, county of Allegan, State of Michigan, have invented certain new and useful Improvements in Sorting Machines, of which the following is a specification.

This invention relates to improvements in sorting machines.

10 The main object of this invention is to provide an improved sorting machine for sorting or grading fruit which minimizes the labor of the sorters, enabling the performance of a relatively large amount of work 15 and also accurate work.

Objects pertaining to details and economies of construction and operation of my invention will definitely appear from the detailed description to follow.

20 I accomplish the objects of my invention by the devices and means described in the following specification. The invention is clearly defined and pointed out in the claims.

25 A structure which is a preferred embodiment of my invention is clearly illustrated in the accompanying drawing forming a part of this application, in which:

Fig. I is a plan view of my improved 30 sorting or grading machine partially broken away.

Fig. II is a side elevation partially broken away.

In the drawing similar reference characters refer to similar parts in all of the views.

The structure of my improvements illustrated comprises a main frame consisting of side pieces 1, cross bars 2 and suitable uprights or legs 3. The side pieces 1 constitute 40 side members for the outer ways.

I have illustrated this frame in detail as it will be understood that it is to be made of the desired length and rigidity to properly support the parts.

45 I provide a pair of outer ways designated generally by the numerals 4 and 5 and an intermediate way 6. These ways are separated by the way side pieces 7 disposed at the sides of the intermediate way, and corresponding side pieces 7' are disposed at the sides of the outer way.

The ways comprise belts 8, 9 and 10 sup-

ported at their outer ends on the pulleys 11, 11 and 11' having a common shaft 12. The pulleys 11, 11 are fastened securely to the common shaft 12, but the pulley 11' for the belt 10 is loose or rotatable on the shaft 12. 55

The bearings 13 of this shaft 12 are adjustably supported in the slides 14, screws 15 being provided for adjusting the bearings. 60

The pulleys 16 and 17 for the return end of the belts 4 and 5 are fixed to the shaft 18 which is extended to one side of the machine and provided with the sprocket 19. 65 The pulley 20 for the return end of the intermediate belt 10 is fixed to the intermediate shaft 21 which is extended to the side of the machine and provided with a sprocket 22 connected to the sprocket 19 by the 70 sprocket chain 23.

The sprocket 19 is larger than the sprocket 22 so that the speed of the intermediate belt exceeds that of the outer belts, thereby adding to the capacity of the intermediate belt. 75

The intermediate belt 10 is a combined driving belt and "cull" carrying belt and is provided with a driving pulley 24 mounted on the shaft 25 carried by the forward legs of the main frame, the shaft having a driving pulley 26. An adjustable pulley 34 acts as a supporting idler and belt tightener for the belt 10. 80

The upper reaches of the belts are supported by conveyor ways 27 disposed between the pulleys so that the belts slide thereon and are supported horizontally. 85

The lower return reaches of the belts 8 and 9 are supported by rollers 35 so that they do not sag down in the way of the sorters as they sit at the sides of the machine. 90

At the ends of the ways I provide bins 28, 30 and 31. The bins 28 and 30 have canvas bottoms and at their outer ends I attach canvas discharge tubes 29. A part of the inner wall of these tubes is cut away and the edge attached at 36 to the canvas bottom of the bin, providing in effect a bottomless discharge tube extending upwardly at the front end of the bin and securely attached to the rods 37. This forms a means for discharging the fruit from the bins into a basket or receptacle with a minimum bruising effect. To prevent the discharge, the 95 100

lower end of the tube may be gathered up and folded over the rods 37, allowing the fruit to accumulate into the bin until the discharge tube is swung down into a basket 5 or receptacle.

The way 6 is provided with a laterally disposed bin 31 having a discharge door 32 held normally in closed position by the latch 33.

10 With the parts thus arranged the fruit or vegetables to be sorted are delivered upon the conveyor belts, preferably from a sizing machine, which delivers fruit, for example, of a minimum size of $2\frac{1}{2}$ inches in diameter 15 on to the belt 4 and fruit of a minimum size of $2\frac{1}{4}$ inches in diameter to the belt 5, the first being the grade 1 and the second, grade 2, in the case of apples. The sorters standing or sitting at the sides of the machine remove blemished or unsuitable fruit 20 from the main conveyor and place it on the "cull" conveyor.

By carrying the fruit or vegetables along before the operator for a considerable period 25 of time it is possible to handle a large amount of material with comparatively few sorters and with a minimum amount of effort on the part of the sorters, and very accurate work may be done.

30 Having thus described my invention, what I claim as new and desire to secure by Letters Patent is:

1. In a structure of the class described, the combination of a supporting frame, outer 35 and intermediate conveyors disposed side by side and comprising conveyor belts, the intermediate conveyor being shorter than the outer, front, rear and intermediate shafts disposed transversely of said belts, said rear and intermediate shafts being extended to one side and being provided with 40 sprockets, the front shaft being adjustably supported, pulleys for said outer belts fixed to said front and rear shafts, pulleys for 45 the intermediate belt, the rear pulley being fixed to said intermediate shaft and the front pulley being rotatable on said front shaft, a connecting chain for said sprockets, said sprockets being of such relative size that 50 the intermediate belt travels faster than the outer belts, and a driving pulley for said intermediate belt.

2. In a structure of the class described, the combination of a supporting frame, outer 55 and intermediate conveyors disposed side by side and comprising conveyor belts, the intermediate conveyor being shorter than the outer, front, rear and intermediate shafts disposed transversely of said belts, said rear 60 and intermediate shafts being extended to one side and being provided with sprockets, pulleys for said outer belts fixed to said front and rear shafts, pulleys for the intermediate belt, the rear pulley being fixed 65 to said intermediate shaft and the front pulley to said intermediate shaft and the front

pulley being rotatable on said front shaft, a connecting chain for said sprockets, said sprockets being of such relative size that the intermediate belt travels faster than the outer belts, and a driving pulley for said intermediate belt.

3. In a structure of the class described, the combination of a supporting frame, outer and intermediate conveyors disposed side by side and comprising conveyor belts, the intermediate conveyor being shorter than the outer, front, rear and intermediate shafts disposed transversely of said belts, said rear and intermediate shafts being extended to one side and being provided with 75 sprockets, the front shaft being adjustably supported, pulleys for said outer belts fixed to said front and rear shafts, pulleys for the intermediate belt, the rear pulley being fixed to said intermediate shaft and the front pulley being rotatable on said front shaft, a connecting chain for said sprockets, and a driving pulley for said intermediate belt.

4. In a structure of the class described, the combination of a supporting frame, outer and intermediate conveyors disposed side by side and comprising conveyor belts, the intermediate conveyor being shorter than the outer, front, rear and intermediate shafts disposed transversely of said belts, said rear and intermediate shafts being extended to one side and being provided with sprockets, pulleys for said outer belts fixed to said front and rear shafts, pulleys for the intermediate belt, the rear pulley being fixed to said intermediate shaft and the front pulley being rotatable on said front shaft, a connecting chain for said sprockets, and a driving pulley for said intermediate belt.

5. In a structure of the class described, the combination of a supporting frame, outer and intermediate conveyors disposed side by side and comprising conveyor belts, the intermediate conveyor being shorter than the outer, front, rear and intermediate shafts disposed transversely of said belts, pulleys for said outer belts fixed to said front and rear shafts, pulleys for the intermediate belt, the rear pulley being fixed to said intermediate shaft and the front pulley being rotatable on said front shaft, a driving pulley for said intermediate belt, and driving connections for said rear and intermediate shafts whereby the belts are driven at different speeds.

6. In a structure of the class described, the combination of a supporting frame, outer and intermediate conveyors disposed side by side and comprising conveyor belts, the intermediate conveyor being shorter than the outer, supporting and driving pulleys for said belts, the pulleys at the front ends of said ways having a common 125

shaft, pulleys for the rear ends of the outer belts, a pulley for the rear end of the intermediate belt, driving connections therefor to said rear pulleys of said outer belts, 5 a driving pulley for the intermediate belt which constitutes a driving belt, conveyor side members disposed at the sides of said

belts, and conveyor way members disposed between said pulleys for supporting the upper reaches of said belts. 10

In witness whereof, I have hereunto set my hand.

DWIGHT W. WADSWORTH.
